US0D1022957S

(12) **United States Design Patent** (10) **Patent No.:** **US D1,022,957 S**
(45) **Date of Patent:** **** Apr. 16, 2024**

(54) **SPEAKER**

(71) Applicant: **HUAWEI TECHNOLOGIES CO., LTD.**, Shenzhen (CN)

(72) Inventor: **Wenxue Li**, Shenzhen (CN)

(73) Assignee: **HUAWEI TECHNOLOGIES CO., LTD.**, Shenzhen (CN)

(**) Term: **15 Years**

(21) Appl. No.: **29/764,150**

(22) Filed: **Dec. 29, 2020**

(30) **Foreign Application Priority Data**

Jun. 29, 2020 (CN) 202030339176.6

(51) **LOC (14) Cl.** **14-01**

(52) **U.S. Cl.**

USPC **D14/216**

(58) **Field of Classification Search**

USPC D14/314, 341, 356, 362, 363, 365, 366, D14/368, 369, 388, 432, 498-507, 509, D14/510, 129, 131, 159, 168, 169, 171, D14/172, 175, 188, 194, 199, 202, 203, D14/203.1, 203.3, 203.4, 203.6, 203.7, D14/204, 209.1-216, 217, 221, 218, 261, D14/211, 208, 200, 187, 224, 173, 207

CLAIM

The ornamental design for a speaker, as shown and described.

DESCRIPTION

FIG. 1 is a front view of a speaker, showing my new design; FIG. 2 is a front perspective view thereof;

FIG. 3 is a back view thereof;

FIG. 4 is a left side view thereof;

FIG. 5 is a right side view thereof;

FIG. 6 is a top view thereof; and,

FIG. 7 is a bottom view thereof.

The broken lines in the figures show portions of the speaker that form no part of the claimed design.

1 Claim, 7 Drawing Sheets
